UNITED STATES PATENT OFFICE.

WILLIAM ROY MORRIS, OF BOISE, IDAHO, ASSIGNOR, BY MESNE ASSIGNMENTS, TO MINERAL DEVELOPMENT COMPANY, OF BOISE, IDAHO, A CORPORATION OF IDAHO.

CONCENTRATOR AND FLOTATION SEPARATOR.

Application filed February 23, 1922. Serial No. 538,723.

To all whom it may concern:

Be it known that I, WILLIAM ROY MORRIS, a citizen of the United States of America, residing at Boise, Idaho, have invented new and useful Improvements in Concentrators and Flotation Separators; and I do declare the following to be a full, clear, and exact description of the invention, such as will enable others skilled in the art to which it appertains to make and use the same, reference being had to the accompanying drawings and to figures of reference marked thereon, which form a part of this specification.

15 This invention relates to the art of separating, classifying and concentrating finely divided ores or other mixed and ungraded materials composed of particles of different specific gravity.

20 The object of the invention is to recover the highest possible percentage or values of the heavier ingredients of a mixture of solid particles in the shortest period of time.

The invention consists in the process and apparatus for practicing it particularly explained in the ensuing description, illustrated in the accompanying drawings and defined in the appended claims.

25 In the drawings, in which like reference characters indicate like parts throughout the several views,

Figure 1 is a plan view of one embodiment of the invention;

Fig. 2 is a side elevation thereof;

30 Fig. 3 is an end elevation of the same;

Fig. 4 is a vertical longitudinal section through a separating and concentrating tank or container forming a part of the apparatus illustrated in Figs. 1 to 3;

35 Fig. 5 is a transverse vertical section on the broken section line in Fig. 4, viewed in the direction indicated by arrow 5, parts of the structure being shown broken out to disclose pipes in the rear thereof;

40 Fig. 6 is a transverse vertical section of said broken line in Fig. 4 viewed in the direction indicated by arrow 6, parts of certain partitions having been broken out;

Fig. 7 is a perspective view of a guiding and collecting plate forming a part of the apparatus, and

Fig. 8 is a section of a fragment illustrating the connection of a suspending rod to the separating and concentrating tank.

In the drawings there is illustrated a preferred embodiment of an apparatus adapted to practice the improved process.

The open oblong frame 1 of the apparatus is substantially rectangular in plan and elevation and supports an oblong separating or concentrating tank or container 2, which is suspended by laterally diverging hangers or rods 3 that are attached at their lower ends to the sides of the tank somewhat below its top and at their ends to cross beams 60 on the upper portion of the frame by means of universal jointed connections such as swiveled ball-joints 4. The suspending rods 3 on opposite sides of the tank are shown to diverge laterally, but they may be made to 65 set parallel or to converge laterally as desired, the pairs at opposite ends are in transverse planes parallel with each other. The said means of suspension would permit of a 70 sidewise vibration and rocking movement 75 of the tank or a parallel oscillatory movement in either direction as desired.

Positioned above what is here designated the rearward end of the container 2 is a material receiving hopper or chute 5 through 80 which finely divided materials to be separated are fed into the container or tank 2. This chute 5 is attached to container 2 by means of supporting braces 6 and 6^a and is held rigid therewith so that when the container is moved the chute moves with it as a fixed part thereof. Two sets of braces 6, 6^a may be kept of such proportions that the discharge end of the chute 5 may be disposed beneath the surface of the liquid mass or at 85 the surface.

Positioned within said container 2 and adjacent the forward end thereof is a rearward and downward inclined transversely curved collecting plate 7 which may be made of soft 90 copper or any other suitable non-vibrating

or relatively inelastic substance. This plate 7 is attached to and supported by the slanting plate 8 (at its rear end) and the vertically arranged spaced plates 9, all of which 5 are fixedly attached to the interior of the

5 container. Plate 7 is so positioned that it tends to direct the heavy material in the container towards a point adjacent the rear end of the said container.

10 In the rear end of the container 2 and at the bottom thereof is a curved recess or amalgamating chamber 10 having a transversely curved bottom which is intended for collecting the concentrates and amalgamating the metal contents, and which is in communication with a discharge opening 11, as best shown in Fig. 5 of the drawings, through which the concentrates pass into an adjacent auxiliary compartment 12 from 15 which they are pumped or jettied into a storage container (not shown) through the pipes 13, 13^a and 14, the open lower ends of said pipes being opposed and spaced from each other in said compartment. The concentrates in the compartment 10 may be discharged by gravity through the outlet 32 leading from the lower portion of said compartment to the exterior. Said outlet 32 may be opened and closed by a plug or any 20 suitable closure.

Positioned transversely across the container 2 and adjacent the bottom thereof is a perforated water inlet pipe 15 which receives its water through pipe 16, which, in 25 turn, is coupled to the pipe 13^a and to a water feed pipe 17 extending up to the receiving chute 5 into which the latter is adapted to discharge water to mingle with the material being fed into said chute. 30 Pipes 13^a, 13, 16 and 17 are in communication with each other and are provided with suitable valves so that water may be pumped through pipe 13^a into pipe 13 or into pipe 16 to be discharged through pipe 15, or into 35 pipe 17 to be discharged into the chute 5, by adjusting the valves in proper relation.

A pump 29 is attached to the rear end of frame 1 at the lower edge thereof and is driven by a pulley 28 which, in turn, is 40 driven by the pulley 26 through the belt 27. The pulley 26 is mounted on the shaft 20 and is operated thereby. The pump 29 receives water from an outside source through pipe 29^a and pumps it through the 45 pipe 13^a (which has a flexible section) and through the pipe 16 to the perforated pipe 15 in the lower portion of the container 2 when the valves are properly adjusted to this end. The water is pumped through the 50 pipe 13 and jettied across the space between the open ends of pipes 13 and 14 entraining liquids and solids in chamber 12 and forcing them up pipe 14 and out of either the outlet 30 or the terminal outlet 31 in case 55 the valves are adjusted to so permit. The

water is fed through pipe 17 into the receiving chute 5, there to be admixed with the dry material entering the said chute provided another suitable adjustment of the valves is made.

70 Positioned at the bottom of the container 2 and underneath the curved plate 7 is a cock 33 for drawing off any leakage that may accumulate beneath the said plate. The overflow cock 34 positioned near the upper 75 edge of the receiving chute 5, is intended to discharge any excess water that may accumulate in the said chute.

A stepped pulley 18, mounted on the shaft 19, may be utilized to rotate the shaft 19, 80 and the shaft 19 drives the shaft 20 through the intermeshing miter gears 21, 21^a. Pulley 18 may be belted to any suitable source of power.

Angularly adjustable eccentrics 22 and 85 23 are mounted on the shaft 19 for vibrating the container sidewise and an angularly adjustable eccentric 24 is positioned on the shaft 20 and is adapted to vibrate the said container endwise. The eccentric 24 may 90 be set to impart greater amplitude of movement than the eccentric 22. Likewise the eccentric 22 may be set to impart greater amplitude of movement than the eccentric 23, that is, each eccentric may be set to give 95 any desired amplitude of vibration within the limits of its construction.

Shafts 19 and 20 are mounted in hangers or bearings 25 at one side and end of the 100 frame 1.

105 Miter gear 21 is of a different size and has a different number of teeth than miter gear 21^a. The gear ratio of the number of teeth on the respective gears should be such that they have no common divisor; gear 21 may have, for example, 19 teeth and gear 21^a 11 teeth, or any multiple of these numbers.

The adjustable eccentrics 22, 23 and 24 on 110 the shaft 19 and 20 are attached to container 2 by means of links and universal couplings such as ball and socket joints 35.

A hand nut or threaded adjusting wheel 36 is disposed between spaced brackets on one side of the receiving chute 5 and engages 115 a threaded rod 36^a that is connected with a butterfly valve 37 in the lower or discharge end of the receiving chute 5 and is adapted to adjust the position of said valve for regulating the feeding of the material.

120 A lip or overflow guiding flange 38 is formed at the upper end of the container 2 at the forward end thereof and is adapted to direct the outflow of the material of least specific gravity.

125 Shaft 20 is provided at its free end with a pulley 39 which may be connected with a source of power to operate the apparatus in case it is inconvenient to operate the same through the medium of the stepped pulley 18.

In utilizing the apparatus, gangue or other material to be separated is introduced into the chute 5 where it is admixed with water from the pipe 17 and passes down past the valve 37 into the rear end of the container or tank 2, adjacent the inclined plate 8 sloping from the foot or lower end of the collecting plate 7. It will be understood that water will be flowing through the perforated pipe 15 underneath the mass of material which assists in carrying the lighter materials toward the top of the container. The streams of water issuing from pipe 15 also prevent the material from matting or caking up thereby clogging the apparatus. Other means of introducing the water at or near the bottom of the container may be used. The pulley 18 or the pulley 39 is then rotated, thereby rotating the shafts 19 and 20 which, in turn, through the medium of the adjustable eccentrics 22, 23 and 24 may impart an uneven sidewise rocking and vibratory movement as well as a parallel endwise oscillatory movement to the container 2, the several component forces imparting a complex and continually varying movement. The container may be so suspended and vibrated that the amplitude of lateral vibration is increased from the top toward the bottom or from the bottom towards the top, and from the front toward the rear or from the rear towards the front of the container while all portions of the container move endwise equal distances. The object is to cause the lighter materials to move toward the top and the heavier materials to move toward the bottom, and to have an equalized extent of movement in proportion to their weight, and to place each particle in the mass in position according to its specific gravity, and furthermore to cause the lighter particles to move toward the front and the heavier parts to move toward the rear.

In operating the apparatus to carry out gravity separation, the material is fed into the container below the gangue at substantially the point of mean specific gravity of the entire mass and at the point where the different particles seek the position in the container at which the conditions as to separation are best adapted to their individual specific gravity. Thus the apparatus separates the materials by placing each particle in its position with relation to its specific gravity and not with relation to the specific gravity of the particle. This is accomplished by the proper upward and rearward movement of water thru the mass of material being concentrated, and also because of the fact that the vibration in one direction are broken by an uneven number of vibrations at substantially right angles so that the nodes of vibration occur at distant intervals, as, for example with gears 21 and 21^a having 11 and 19 teeth respectively,

the nodes occur once in 11 sidewise vibrations and once in 19 endwise vibrations.

The eccentrics are so constructed that the centers of the paths of sidewise vibrations and endwise vibrations can be changed at will, so as to impart any motion required (within the mechanical limits imposed) according to the velocity of treatment and nature of the materials to be concentrated.

The inclined plate 7 intercepts and receives the slimes of fine concentrates that are moving slowly to the front, which, when making contact with the plate are precipitated and turned back, traveling slowly along the inclined toward the rear. This insures a high efficiency of separation of the slimes. The plate 7 may be coated with quicksilver and used as an amalgamator if desired.

My invention may be used with oil in the flotation process of separation by raising the material receiving trough so that the feed will be introduced at the surface of the mass, thus mixing the material with the oil and fine particles floated by it. The action of the machine is then so modified that the oil and fine metallic values imprisoned by it are carried to the top and front while the gangue is carried to the bottom and rear.

Many minor changes in detail of construction may be resorted to without departure from the spirit of the invention.

I claim:—

1. A method of separating or classifying particles of different characteristics from a mass of finely divided material which consists in charging a container with said material mixed with a quantity of liquid sufficient to provide for suspension of the particles therein and imparting vibratory movements to said container by forces acting substantially horizontally at right angles to each other, so that one end of said container may have a greater amplitude of movement at one of its ends than at its other end.

2. A method of continuously separating or classifying particles of different characteristics from a mass of finely divided material which consists in feeding into the container a stream of material, supplying sufficient liquid to provide for suspension of the particles; agitating the container in such manner as to concentrate the particles tending to sink in the liquid at one portion of the container and feeding the material into the mass of liquid and material substantially above the point where the sinking particles concentrate, and means for vibrating said container so that one of its ends may have a greater amplitude of vibration than its other end.

3. A method of continuously separating or classifying particles of different characteristics from a mass of finely divided material which consists in feeding into the con-

tainer a stream of material, supplying sufficient liquid to provide for suspension of the particles; agitating the container in such manner as to concentrate the particles tending to sink in the liquid at one portion of the container and feeding the material into the mass of liquid and material substantially above the point where the sinking particles concentrate but beneath the surface of the liquid.

4. The method of separating or classifying particles of different characteristics from a mass of finely divided material suspended in liquid within an oblong container, which consists in simultaneously vibrating, substantially horizontally, said container both lengthwise and sidewise thereof, the lengthwise vibrations being imparted in constantly changing time relations with respect to the sidewise vibrations, the sidewise vibrations of one end of the container may be of greater amplitude than the vibrations of the other end; thereby concentrating the particles that tend to sink in the liquid adjacent the end having the greater amplitude of vibration, and feeding additional material and liquid into the mass of material and liquid substantially at the location of the concentrated particles.

5. In a separating and concentrating apparatus, an oblong container, means for sustaining said container so that it may move universally in approximately horizontal directions, a mechanism connected to said container exerting force in a direction lengthwise of the container to vibrate it, and separate spaced mechanisms exerting forces to vibrate the container laterally so that the time ratio and amplitude of such vibrations may be changed at will.

6. A gravity concentrator or separator comprising a frame, a container positioned within said frame, a plurality of laterally divergent supporting rods connecting the top of said frame with said container, universal joints at the ends of said rods, a material receiving chute carried by said container, and means positioned on said frame for imparting a lengthwise back and forth movement and a sidewise back and forth movement to said container, so that one end thereof may have a greater amplitude of movement than the other.

7. A gravity concentrator or separator comprising a frame, an oblong container positioned within said frame, a valved receiving chute positioned so as to discharge at a definite point near the rear end of said container, a collecting plate or collecting plates positioned within said container and inclining downward from the forward end thereof to a concentrating point adjacent the discharge end of said receiving chute, and means for reciprocating said container in longitudinal and transverse directions,

the transverse movement at the opposite ends of said container being of the same or different amplitudes as may be desired.

8. A gravity concentrator or separator comprising a frame, a container movably mounted within said frame, a receiving chute disposed at the rear end of said container, an amalgamating chamber for concentrates formed at the bottom rear end of said container and an auxiliary concentrates receiving compartment adjacent said amalgamating chamber, a partition disposed between said compartment and chamber, said partition being provided with a communicating opening, and means for discharging water adjacent the bottom of said chute.

9. A gravity concentrator or separator comprising a frame, a container movably mounted within said frame, a receiving chute carried by said container, a perforated pipe extending transversely across and at the bottom of said container and at the outlet end of said receiving chute and means for supplying water to said pipe.

10. A gravity concentrator or separator comprising a frame, a container movably mounted therein, a collecting plate within said container inclining downwards from an overflow outlet, a material receiving chute adapted to discharge adjacent the lower end of the collecting plate, means for forcing water in at or near the bottom of said container beneath the discharge end of the chute, said means also having a branch connection with the upper portion of said receiving chute and means for removing concentrates from said container.

11. A gravity concentrator or separator comprising a frame, a container movably mounted within said frame, means for shaking said container in longitudinal and transverse directions, the amplitude of transverse movement of the container being the same or greater at one end than at the other, an amalgamating chamber at the bottom and rear of said container, an auxiliary concentrates receiving compartment adjacent and communicating with said chamber, a partition disposed between said compartment and chamber, and means for discharging the concentrates from the auxiliary chamber.

12. A gravity concentrator or separator comprising a frame, a container movably mounted within said frame, a valved receiving chute at the top and rear end of said container, an amalgamating chamber at the bottom and rear end of said container, an auxiliary compartment adjacent said chamber and in communication therewith, a perforated water inlet pipe or pipes at or near the bottom of said container and means for discharging the contents from said auxiliary compartment.

13. A gravity concentrator or separator

comprising a frame, a container suspended within said frame, a receiving chute at the top and rear end of said container, a transversely curved collecting plate positioned at the forward end of said container and inclining downward toward the rear end thereof, the lower end of said plate being substantially directly below the discharge

end of said receiving chute, means for forcing water into the bottom of said container 10 beneath the discharge end of the chute, and a discharge outlet at the top and forward end of said container and collecting plate, and means for reciprocating said container in longitudinal and transverse directions.

WILLIAM ROY MORRIS.
